United States Patent Office.

WILLIAM ROEMER, OF NEWARK, NEW JERSEY.

Letters Patent No. 98,299, dated December 28, 1869.

IMPROVEMENT IN LOCKS FOR SATCHELS AND CARPET-BAGS.

The Schedule referred to in these Letters Patent and making part of the same.

To all whom it may concern:

Be it known that I, WILLIAM ROEMER, of Newark, in the State of New Jersey, have invented certain Improvements in Locks for Satchels, Carpet-Bags, and similar articles, of which the following is a specification.

My invention relates to the arrangement of the lock on the outside, at one side of the frame, and the peculiar construction of the staple, in such a manner that the said staple will hold the two parts of the frame, and, consequently, the satchel or carpet-bag, firmly together, and closed, without throwing any strain upon the mechanism of the lock.

Figure I represents a side view of part of the frame, with the lock attached, having the outside plate of the lock removed.

Figure II is a cross-section of the same.

A represents part of the outer frame, and

A', part of the inner frame, to which the material forming the satchel or carpet-bag, &c., is attached.

These frames are hinged together at their lower ends, and otherwise constructed in the usual manner.

Against the outside of the inner frame A', the lock B is attached.

This lock B is provided with a projecting piece or plate, C, coming (when the satchel or bag is closed) in contact with the outer edge of the upper or outer frame A, to prevent said inner frame A' being pressed too far inward.

To the top of the outer frame A, the staple D is attached, by means of the plate n, fastened to said frame A, and on which this staple D is hinged.

This staple D is bent, forming a right angle, one leg of which, r, is hinged to the plate n, and runs across the top of the outer frame A, and the other leg, w, extends downward, entering the lock B, and firmly embraces the plate or projection, C, on the lock B, so as to keep the two parts of the framing tight together against any internal pressure, resulting from the filling too full of the satchel or bag.

On one side of the leg, w, of this staple D, a recess, x, is made, into which a projection, a, fast to the

lock-bolt s, operated by means of a key, or in any suitable manner, is made to fit, for the purpose of holding the staple D in its place, and locked.

Locks are at present attached either upon the top of the frame, or on the inside of the same. When placed on the top, they are very liable of being bent or broken off when the satchel or bag falls or is thrown on the ground, while, with my improvement of fastening the lock against the outside, on the side of the frame, the same is perfectly protected, and can be made of any desired size to offer the necessary security.

When the lock is placed at the inside of the frames, the same can be made only very small, on account of the limited space between the frames.

The placing of the lock either upon the top, or on the inside of the frame, necessitates the attachment of hooks or staples to the inside of the inner frame, which are acted upon by the lock-bolt, and whereby the whole strain, to keep the satchel or bag closed, is thrown upon this lock-bolt, or upon the mechanism of the lock, causing thereby, frequently, disarrangements of the lock.

The necessary attachment of hooks or staples to the inside of the frames, by the present arrangement of the lock, causes, likewise, very often, considerable damage to the articles placed in the satchel or bag, while being put in or removed therefrom, all of which disadvantages are removed by my improvement.

What I claim as my invention, and desire to secure by Letters Patent, is—

1. Attaching the lock B, on the outside, against the side of the frame, for satchels and carpet-bags, in combination with a staple, D, attached to the top of the frame, operating together in the manner and for the purpose described.

2. The projecting piece or plate C, in combination with the lock B and inner frame A', substantially as and for the purpose set forth.

WILLIAM ROEMER.
